DRAIN CLEANER

Herman W. Whitaker, Port Arthur, Tex., assignor of forty per cent to Carolyn Jernigan, Port Arthur, Tex.

Application December 9, 1938, Serial No. 244,860

3 Claims. (Cl. 285—44)

This invention relates to a device for flushing drains of sinks and the like to effect cleaning thereof when clogged.

The primary object of the present invention is to provide a device of this character whereby a water lead is had from a faucet to a drain pipe or the like, so that said pipe can be cleaned with dispatch and without possibility of leakage at the faucet or at the inlet of said drain pipe.

A further more specific object of the present invention is to provide a device of the above character wherein the discharge end or outlet nozzle of the same is provided with means engageable with the guard cross of the drain pipe so as to maintain a tight union between said nozzle and the inlet end of the drain pipe and prevent leakage at this point without the necessity of maintaining pressure thereon from the hand of the user.

Another object of the invention is to provide a device of this kind which is efficient in use and extremely simple and durable in construction.

The present invention consists in the novel form, combination and arrangement of parts hereinafter more fully described, shown in the accompanying drawing and claimed.

In the drawing:

Figure 1 is a transverse sectional view through a sink showing the device constructed in accordance with the present invention applied to a faucet and the drain pipe, the device being partly broken away and in section.

Figure 2 is an enlarged fragmentary vertical section on line 2—2 of Figure 1.

Figure 3 is an enlarged perspective view of the hook-carrying washer forming part of the construction shown in Figures 1 and 2; and

Figure 4 is a fragmentary perspective view of a modified form of metal reinforcing tube for the outlet nozzle of the device wherein the guard cross engaging hooks are carried directly by said reinforcing tube.

Referring in detail to the drawing, A indicates a kitchen sink, B the water faucet which supplies water to the sink, and C the main inlet fitting having the sunken guard cross 5 and providing the connection between the sink and the drain pipe 6.

The present drain cleaner or flusher comprises a flexible hose 7 of a length to extend from the faucet B to the drain outlet fitting C. One end of the hose has a flared mouth 8 to fit various sizes of faucet mouths, and a clamp collar 9 to effect a tight union between the mouth 8 and the mouth of the faucet. However, it will be obvious

that a suitable hose coupler may be fitted and clamped in the mouth 8 in case the faucet should have a threaded mouth.

At the opposite end, the hose has a nozzle 10 of greater external diameter than the hose and terminating at its outer extremity in an enlarged truncated conical head 11 which is highly resilient so that the same may be forced well into the drain outlet fitting C to provide a tight union between the nozzle and said fitting C so that leakage at this point is prevented. The nozzle is internally reinforced by means of a coaxial metallic reinforcing tube 12 molded therein so as to prevent undue restriction of the passage through the hose at the nozzle when the latter is forced into the drain fitting C.

In order to maintain the tight union between the head 11 of nozzle 10 and the fitting C, after the water pressure has been turned into the hose 7 by opening the faucet B, and without maintaining downward pressure on the head 11 by the hand of the user, I provide means on the head 11 engageable with the guard cross 5. This means may consist of spaced oppositely facing and diametrically opposed depending hooks 13 engageable with a member of the guard cross 5 upon slight turning of the nozzle 10 after insertion of its head 11 within the fitting C. As shown in Figures 1 to 3 inclusive, the hooks 13 may be formed integral with a washer 14 fitted on the projecting lower end of reinforcing tube 12 and maintained against the outer or lower end of the head 11 by spinning the lower end of tube 12 outwardly to provide a flange 15 clamping the washer 14 against the head 11 with the central opening 16 of the washer 14 concentric with the passage through the nozzle 10. Should frictional clamping engagement of the washer 14 be insufficient to prevent turning thereof relative to the head 11, said washer 14 may be suitably held against turning such as by providing the same with spurs or prongs arranged to bite into the head 11 as commonly employed in other arts for a similar purpose.

As shown in Figure 4, the hooks 13 may be formed integral with the outer end of reinforcing tube 12 to function in the same way, instead of providing the hooks on a washer as in Figures 1 to 3 inclusive. Otherwise, the purpose and manner of use will be exactly the same in both cases.

With the device applied as above described, the water delivered by the faucet B, when the latter is opened, will be forced under pressure directly into the drain pipe 6 without leakage at the faucet or the outlet drain fitting C. In this manner, the

drain pipe 6 will be thoroughly cleaned with dispatch.

What I claim as new is:

1. A drain pipe cleaner comprising a flexible 5
hose provided with means at one end for attachment to a faucet mouth, the opposite end of the
hose having a nipple terminating in an enlarged
truncated conical head for fitting in a drain outlet
fitting, an axial metallic reinforcing tube
molded in said nipple to prevent restriction of
the passage through the latter when the head of
said nipple is forced into the outlet drain connection, and oppositely facing diametrically opposed
projecting hooks carried by the lower end of said
10 tube at the outer end of said head and engageable
with a member of the guard cross of the drain
outlet fitting to maintain a tight union between
said head and said fitting.
2. A drain pipe cleaner comprising a flexible
20 hose provided with means at one end for attachment
to a faucet mouth, the opposite end of the
hose having a nipple terminating in an enlarged
truncated conical head for fitting in a drain outlet
fitting, an axial metallic reinforcing tube molded
25 in said nipple to prevent restriction of the passage
through the latter when the head of said nipple
is forced into the outlet drain connection, oppo-

sitely facing diametrically opposed projecting
hooks carried by the outer end of said head and
engageable with a member of the guard cross of
the drain outlet fitting to maintain a tight union
5 between said head and said fitting, a washer dis-
posed against the outer end of said head and pro-
vided with said hooks, and an outturned flange on
the outer end of said reinforcing tube clamping
the washer tightly between the same and the
outer end of the head. 10

3. A drain pipe cleaner comprising a flexible
hose provided with means at one end for attachment
to a faucet mouth, the opposite end of the
hose having a nipple terminating in an enlarged
truncated conical head for fitting in a drain outlet
fitting, an axial metallic reinforcing tube molded
in said nipple to prevent restriction of the passage
through the latter when the head of said nipple
is forced into the outlet drain connection, and
oppositely facing diametrically opposed projecting
hooks carried by the outer end of said head and
engageable with a member of the guard cross of
the drain outlet fitting to maintain a tight union
15 between said head and said fitting, said hooks
being integral with the outer end of said reinforce-
ing tube. 20
